ART OF CRACKING HYDROCARBONS

Filed Jan. 28, 1922

Edward W. Scarce

By Robert Webb Dinesen
M. A. F. S.

UNITED STATES PATENT OFFICE.

EDWARD W. ISOM, OF WINNETKA, ILLINOIS, ASSIGNOR TO SINCLAIR REFINING COMPANY, OF CHICAGO, ILLINOIS, A CORPORATION OF MAINE.

ART OF CRACKING HYDROCARBONS.

Application filed January 28, 1922. Serial No. 532,351.

In the usual practice of cracking hydrocarbon oils, gas oil, fuel oil or other oil containing heavier hydrocarbons is heated under pressure in a still to a temperature at 5 which a considerable proportion of the hydrocarbon compounds composing such oil is broken down with the formation of lighter hydrocarbon liquids and gases and a certain amount of "carbon". The vapors of the 10 cracked hydrocarbons are conducted from the still to a reflux tower in which the heavier components, such as are unsuitable as components of gasoline or other desired distillate, are condensed and flow back into 15 the body of oil in the still where they intermingle with the contents of the still and undergo further treatment. The vapors of oils of the desired character pass over from the top of the reflux tower to a condenser 20 where the condensate is condensed and from which they are discharged together with fixed gases into a receiving drum from which the condensates are led to suitable storage tanks and the surplus gases to gas 25 holders or burners.

It is necessary that a predetermined temperature be approximately maintained at the head or top of the reflux tower in order to 30 avoid condensing therein vapors which are suitable for the gasoline or other light product which is to be made and which, if condensed within the tower, would be returned to the still and resubmitted to the cracking temperature and more or less broken down 35 into fixed gas. As the reflux tower necessarily radiates considerable heat, a large amount of heat must be supplied to the tower in order to maintain the head temperature and this has been done through the 40 medium of the vapors themselves thus putting a considerable additional burden upon the heating means for the still increasing the fuel consumption and reducing the output. Furthermore, where the distillation 45 takes place entirely under the pressure of the vapors generated, it is necessary to maintain the still charge at a high temperature, to wit, the critical temperature of the liquid under the high pressure of its vapors.

50 The practice, in some systems of distillation, is to lower the distillation point of the oil by partial pressure produced by steam, the steam ordinarily being introduced beneath the surface of the liquid, thus reducing the temperature required. This has the

disadvantage, among others, that the steam entrains considerable of the oil which is too heavy to be properly included within the product of the operation and carries it over into the condenser, and furthermore the 60 presence of the steam, which condenses at a temperature within the condensing range of the desired products of the treatment, puts a heavy additional burden upon the condenser requiring it to be of very materially 65 increased size.

It has also been proposed to introduce an inert gas into the still for the purpose of controlling the pressure therein and in case the fixed gases developed in the still provide 70 a pressure in excess of that desired to release sufficient gas to lower the pressure to the required degree.

My invention involves introducing into 75 and mingling with the vapors evolved from the still and passing through the reflux tower a continuous stream of gas sufficient in amount not only to control the pressure in the still irrespective of the development 80 of vapors thereby but also to assist in carrying the vapors of the desired distillate through the reflux tower to the condenser while introducing oil to be supplied to the operation into the reflux tower in direct 85 contact with the vapors and gases therein thereby absorbing a large part of the heat given off in the refluxing operation in this oil. The pressure, being dependent on the introduced gases, is not subject to the irregularities incident to pressure maintained by 90 the evolved vapors occasioned by variations in evolution and condensation. The stream of gas being continuously introduced, preferably at the bottom of the reflux tower, and continuously exhausted, preferably beyond 95 the condenser, carries the vapors with it up the tower thus reducing the head temperature required to effect the desired cut between the heavier oils which are returned to the still to be re-cracked and the lighter distillate which passes over to the condenser. Cool or unheated gases are used with advantage assisting in cooling and condensing the heavier reflux vapors thus reducing the 100 required capacity of the reflux tower.

105 Preferably the gases employed are hydrogen-containing or hydrocarbon gases and it is convenient and desirable to employ for the purpose the fixed gases given off by the still or by a group of stills. By employing 110

hydrogen-containing or hydrocarbon gases for the purpose given, the advantage of mass action in minimizing the formation of additional quantities of such gases and also of supplying the material for converting more or less of the unsaturated compounds present in the vapors into saturated compounds are secured. A certain part of the gases in the reflux tower are absorbed or dissolved in the fresh stock and in the reflux condensate, thus being returned to the still. If the gases given off by the still are utilized for this purpose, they may be directly and continuously returned, with or without intermediate cooling from the condenser to the tower in a closed circuit, or may be conducted to and from a suitable gas holder.

Preferrably the supply and circulation of the gas is begun only after the initial still charge has been raised nearly to cracking temperature though if desired more or less gas may be introduced at an earlier stage.

In the accompanying drawing I have shown partly in section and partly in elevation and diagrammatically a still system embodying my invention. It is to be understood, however, that the specific disclosure in the drawing and in the following description is for the purpose of exemplification only and that the scope of the invention is defined in the following claims in which I have endeavored to distinguish it from the prior art so far as known to me without, however, relinquishing or abandoning any portion or feature thereof.

In the preferred embodiment of my invention the still 1 may be of any desired or approved type. I have illustrated it, however, as of the type shown in Patent 1,285,200 granted to Sinclair Refining Company, November 19, 1918, upon an application filed by me. As in said patent, the still drum is connected by a down-comer pipe 20 to a pump (not shown) which in turn is connected to a battery of heating tubes from which the oil returns to the still drum through pipe 21, all as fully set out in said patent. The still is provided with a reflux tower 2, condenser 3 and receiving drum 4, each of which may be, except in the respects hereinafter pointed out, of usual type. The vapor dome 5 of the still is connected by vaporline 6 with the reflux tower 2 near the lower end thereof and the pipe 7 extending through the still drum 1 and into the down-comer pipe 20, leads reflux condensate from the bottom of the tower to said pipe. The tower may be provided as usual with baffles 8 and is connected by vapor-line 9 with condenser 3. The latter is connected to the receiving drum which receives condensate from said condenser and is provided with an outlet pipe 10 for condensate and an outlet pipe 11 for leading the fixed gases from the still to a gas holder. The valve

12 may be used to regulate the flow of the gas from the receiving drum to the holder. Fresh stock may be fed into the tower through the inlet pipe 13 and, dripping from baffle to baffle, is heated by the rising column of vapors and gases, and its lighter contents volatilized, and the fresh stock cools the said vapors, condensing their heavier components. The mixture of fresh stock thus preheated and reflux condensate together with any dissolved or absorbed gases enters the still through the pipe 7.

The apparatus just described forms no part of my present invention except in so far as it is combined with the features and so modified in the respects hereinafter described.

My invention involves the provision of a pipe 22 extending into the lower end of the reflux tower for introducing fixed gases 85 thereinto and connected to a pump 23 which is connected on its suction side by pipe 24 to a gas holder, preferably the same gas holder to which pipe 11, above described, connects.

In practicing my invention in its preferred form, the still is partially filled with oil residuum, gas oil or the like and heated. When the oil arrives at the cracking temperature, or somewhat earlier, the pump 23 is 95 set in operation, forcing gas from the gas holder into the bottom of the tower, and the pump preferably remains in operation continuously practically throughout the rest of the run. The pump and connections are 100 of such capacity as to maintain a practically continuous stream or current of fixed gas flowing through the reflux tower, vapor-line, condenser, receiving drum and back to the gas holder from which it is drawn for 105 re-circulation. This stream is more or less reinforced by the fixed gas evolved during the cracking operation. By varying the speed of operation of the pump and adjusting the valve 12 the pressure in the still 110 may be adjusted as desired and independently of the vapor evolution. By injecting the gas into the tower as described it exerts its partial pressure on the still without entraining the heavier oils and assists in carrying the lighter vapors to the top of the tower thus permitting the use of a lower head temperature and effecting a saving in fuel.

I claim:

1. In combination in a pressure still system for cracking oil, a pressure still, a reflux tower in free communication therewith through connections for conveying vapors from the still to the tower and liquid from the tower to the still, a condenser and connections for conveying vapors from the tower to the condenser, means for maintaining superatmospheric pressure on the still and through the tower, means for feeding 125

120

125

130

135

fresh stock into the upper end of the tower directly into the vapor space therein and in direct contact with the vapors, and means for introducing gas into the lower end of the tower directly into the vapor space therein.

2. In combination in a pressure still system for cracking oil, a pressure still, a reflux tower in free communication therewith through connections for conveying vapors from the still to the tower and liquid from the tower to the still, a condenser and connections for conveying vapors from the tower to the condenser, means for maintaining superatmospheric pressure on the still and through the tower, means for feeding fresh stock into the upper end of the tower directly into the vapor space therein, and means for reintroducing into the lower end of the tower directly into the vapor space therein gas escaping from the condenser uncondensed.

3. In combination in a pressure still system for cracking oil, a pressure still, a reflux tower in free communication therewith through connections for conveying vapors from the still to the tower and liquid from the tower to the still, a condenser and connections for maintaining superatmospheric pressure on the still and through the tower, means for feeding fresh stock into the upper end of the tower directly into the vapor space therein and in direct contact with the vapors, and means for introducing hydrocarbon gases into the lower end of the tower directly into the vapor space therein.

4. In combination in a pressure still system for cracking oil, a still, a reflux tower, a condenser and connections between the still, tower and condenser, means for feeding fresh stock into the upper end of the tower directly into the vapor space therein and in direct contact with the vapors and means for introducing gas into the lower end of the tower directly into the vapor space therein.

5. A process for cracking hydrocarbon oils, comprising heating the oil to a cracking

temperature under pressure in a still, passing vapors from the still through a reflux tower, feeding fresh stock into the upper end of the tower in direct contact with the vapors therein, introducing a stream of cool hydrocarbon gases into the lower end of the tower in direct contact with the vapors therein, and conveying admixed fresh stock and reflux condensate from the lower end of the tower to the still.

6. A process for cracking hydrocarbon oils, comprising heating the oil to a cracking temperature under pressure in a still, passing vapors from the still through a reflux tower, feeding fresh stock into the upper end of the tower in direct contact with the vapors therein, introducing a cool stream of uncondensed still gas into the lower end of the tower in direct contact with the vapors therein, and conveying fresh stock and reflux condensate from the lower end of the tower to the still.

7. A process for cracking hydrocarbon oils, comprising heating the oil to a cracking temperature under pressure in a still, passing vapors from the still through a reflux tower, maintaining substantially the still pressure through the tower, feeding fresh stock into the upper end of the tower in direct contact with the vapors therein, introducing cool hydrocarbon gases into the lower end of the tower in direct contact with the vapors therein, and conveying fresh stock and reflux condensate from the lower end of the tower to the still.

8. A process for cracking hydrocarbon oils, comprising heating the oil to a cracking temperature under pressure in a still, passing vapors from the still through a reflux tower, feeding fresh stock into the upper end of the tower in direct contact with the vapors therein, introducing an unheated stream of gas into the lower end of the tower in direct contact with the vapors therein, and conveying admixed fresh stock and reflux condensate from the lower end of the tower to the still.

EDWARD W. ISOM.
